UNITED STATES PATENT OFFICE.

MAER HERMAN, OF CHICAGO, ILLINOIS.

TRESTLE.

1,294,264.

Specification of Letters Patent. Patented Feb. 11, 1919.

Application filed April 19, 1917. Serial No. 163,110.

To all whom it may concern:

Be it known that I, MAER HERMAN, a citizen of Russia, residing at Chicago, in the county of Cook and State of Illinois, have 5 invented certain new and useful Improvements in Trestles, of which the following is a specification.

My invention relates to new and useful 10 Improvements in trestles or adjustable supports, for use by decorators, painters, paper-hangers, calciminers, and the like, and is adapted for use for all kinds of work that requires the operator, or workmen to be supported at varying altitudes, and in rooms of 15 contracted dimensions.

One of the objects of my invention is to provide a foldable and collapsible self-contained supporting structure, that may be used in place of a scaffold, or may be made 20 to serve as supporting bents or horses in the organization of a scaffold.

Another object of my invention is to provide a trestle organization which may readily be folded or contracted into a relatively 25 small compass so that it may conveniently be carried by the workmen, from place to place, or from room to room, and which may quickly be set up and adjusted longitudinally and vertically to varying lengths and 30 heights without the use of tools or parts, such as bolts, screws, clamps or other similar separable devices, commonly used with adjustable trestles of this style of the usual construction.

35 Other and further objects of my invention will become readily apparent, to persons skilled in the art from a consideration of the following description when taken in conjunction with the drawings, wherein:—

40 Figure 1 is a side elevation of the trestle, vertically extended and showing, in dotted lines, the extent to which it may be elongated.

Fig. 2 shows a side elevation of the device 45 when folded and completely contracted.

Fig. 3 shows an end elevation of the device with lower pairs of legs extended and laterally divergent.

Fig. 4 is a similar view before said legs 50 are laterally extended.

Fig. 5 is a plan view, longitudinally contracted.

Fig. 6 is an enlarged view of one of the 55 extendible end sections showing the brace for holding the parts set up and showing

the brace and folding parts in dotted line position in the act of folding together.

Fig. 7 is a transverse section of a fragment taken on line 7—7 of Fig. 6, showing the manner of hinging the braces to each 60 side of the table.

Fig. 8 is a plan view of a fragment of the extendible table.

Fig. 9 is a broken away portion of the extendible leg members. 65

Fig. 10 is a section taken on line 10—10 of Fig. 9.

Fig. 11 is a section taken on line 11—11 of Fig. 9.

Fig. 12 is a section taken on line 12—12 70 of Fig. 9.

In all the views the same reference characters are employed to indicate similar parts.

One embodiment of my invention is shown 75 in the accompanying drawings and comprises, generally, a longitudinally extendible table, or top support 15, upon which the workmen may stand, composed of a series of, preferably, wooden strips or bars 16 to 20, 80 inclusive, which are spaced-apart and held together at their respective ends by cross bars 21 and 22, respectively. This series of strips or bars are substantially as long as the device in its most contracted condition. 85 They are also held in spaced-apart relation, near their middle portions by spacing blocks 23—26, inclusive. Similar, but shorter strips, 27 to 30, at one end and strips, 31 to 34, inclusive, at the other end, providing 90 separated end sections of the structure, alternate in position with the longer strips or bars with relation to which they may be freely and slidably moved, longitudinally. These shorter strips, constitute end sections 95 35 and 36, respectively. The outer ends of these shorter strips, or bars, are held together by bolts 37 that also pass through spacing blocks 38', substantially as wide as the strips or bars 16 to 20 inclusive, so that 100 the latter bars may have free sliding movement with relation to and within the sections 35 and 36. The bolt 37 passes also through relatively thin metal strips or bars 38 and 39, one on each side of the respective sections 35 and 36.

A cross bar 40, turned down at each of its ends, as at 41, is secured to the inner ends of the bars 31—34, by screws 42. A stud 43 is riveted in the downturned end 41, 110

of each of the cross bars 40, one at each end, which stud passes through the metal bars 38 and 39, respectively, and also through the brace members 44, one of which is located 5 on each side of the structure, thereby pivoting the brace members to the cross bars 40. A nut 45 overlies the washer 46 and serves to hold the parts together.

Parallel legs 47 and 48 are preferably 10 made of angle iron, each having its inturned flange 49 cut away, near its upper end, to provide a hinge member 50, which is perforated for the bolt 37 upon which it may be turned, in the act of folding, as shown in 15 Fig. 6. A brace member 54, is hinged, one to each of the leg members 47 and 48, near the respective bottom ends thereof, and is also hinged, as at 55, to the brace member 44. A stop 56 is provided on one of the 20 brace members, so as to hold them in alignment and prevent them being folded in the opposite direction when the device is extended.

A transversely extending, wide, relatively 25 thin member 57, composed of iron or steel, has its ends 58 bent around the longitudinal flanges of the legs 47 and 48 to serve as a guide within which the legs are freely movable. Hinged to the ends of the cross member 57, as at 59, are two legs 60 and 61, made 30 preferably of angle iron, and adapted to snugly overlie the legs 47 and 48, respectively, when the legs 60 and 61 occupy a parallel position, as shown in Fig. 4.

35 A brace member 62 is pivoted to the leg 60, at 63, and to another brace member 64, at 65. The brace member 64 is pivoted to the leg 61, at 66. Another similar brace member 67 is pivoted to the leg 61, at 68, 40 and to another brace member 69, at 70, and the member 69 is pivoted to the leg 60, at 71. When these brace members are in the positions shown in Fig. 3, the legs 60 and 61 are retained in divergent positions thereby, in 45 order to provide a larger base for the structure. To more securely hold the leg in the extended, or divergent positions, as shown in Fig. 3, I may provide other braces 72, hinged at 71 to leg 60 and to another brace 50 member 73, which is hinged at 66, to leg 61, the two brace members being hinged together, as at 74. The brace members 64, 69 and 72 are provided with stops 75 to hold these members in alignment with their 55 respective associate members, when the legs are divergently separated.

When the toggle, composed of the members 72 and 73, is straightened, by downwardly exerted pressure, the legs 60 and 61 60 are thereby moved laterally and the associate brace members are thereby straightened out.

The legs 47 and 48, which bear the table 65 15, are vertically adjustable, with respect to the legs 60 and 61. They are held in ad-

justed position by dogs 76 and 77 that are pivoted to the cross members 57, as at 78 and 79, respectively. The ends of the dogs 76 and 77 engage notches 80 and 81 that are spaced apart on the respective legs. 70 The dogs are held yieldingly in the notches by springs 82 and 83, respectively. A link 84 is pivoted to each of the dogs, as at 85, and each of the links is provided with an outturned end 86, which serves as a thumb 75 button to draw the links together to cause the upper ends of the dogs 76 and 77 to be disengaged from the respective notches. The outturned portion of the link passes through notches 88 made in the cross member 57. When the thumb buttons 86 are released, the springs 82 and 83 press the respective dogs into contact with the respective legs 47 and 48. A plate 89 serves as a 80 partial housing and guide for the dogs and links, within which are contained the springs that yieldingly press the dogs into contact with the legs 47 and 48.

Assuming for example, that the device is folded in its most contracted dimensions, as 90 shown in Fig. 2. In order to set up the device for use, the leg structure at each end, is opened out at right angles to the top or table structure, as shown in Fig. 1, the legs 60 and 61 are then laterally extended in 95 divergent positions and thus held by the braces, as shown in Fig. 3. The supports or legs at each end may then be moved longitudinally of the table, into any intermediate position, between the full lines and 100 dotted lines in Fig. 1, to extend the longitudinal dimensions of the device, after which the table 15, which is directly supported by the pairs of legs 47 and 48 may be vertically moved with respect to the 105 legs 60 and 61, by withdrawing the dogs 76 and 77 from the notches in the legs 47 and 48, by pressing the buttons 86 together, and lifting the table and the supporting legs that are directly hinged thereto 110 and thus the structure may be made to accord with any dimensions within its capacity.

While I have herein shown a single embodiment of my invention, for the purpose 115 of clear disclosure, it will be manifest to persons skilled in the art, that many changes may be made in the general form, arrangement and disposition of the parts within the scope of the appended claims.

Having described my invention, what I 120 claim is:—

1. A structure of the character described, comprising a top member having movable end sections, whereby the top may be extended or contracted; a pair of legs hinged to the outer ends of each of said end sections; another pair of legs, at each end of the table, slidably engaging the first mentioned pair of legs, means to divergently 125 130

extend the bottom pair of legs independently of said first mentioned legs, and braces to hold the parts in extended position.

2. A structure of the character described comprising a longitudinally extendible top member having two like end sections; a pair of substantially parallel legs hinged to the outer ends of each end section; a guide for each pair of legs to permit vertical adjustment thereof; another pair of legs hinged to each guide; means to laterally extend the lower ends of said hinged legs; braces to hold the legs extended, and braces between the top member and the leg structure to hold said leg structure at right angle relation to said top member.

3. A structure of the character described comprising a longitudinally extendible top member having two like end sections; a pair of substantially parallel legs hinged to the outer end of each end section; a cross bar having longitudinally sliding engagement with each pair of said legs; another pair of legs, hinged to each cross bar so as to permit lateral extension of the lower ends of said legs and means for locking said cross bar in adjusted position relative to said first mentioned leg.

4. An apparatus of the character described including in combination, a top member having a member extensible relative to each end, a pair of legs pivoted to each end section, a guide member slidably arranged for vertical adjustment relative to each pair of legs and having means for holding the same in adjusted relation thereto, supplemental legs hingedly connected to each end of each guide member and means for holding said supplemental legs in divergent relation to each other and to said first mentioned legs.

5. An apparatus of the character described including in combination, a top

member, a pair of legs pivoted to each end thereof, said legs being formed of angle irons, a guide member slidably arranged for vertical adjustment relative to each pair of legs, said guide member including a plate having an extended straight portion with its end bent around the longitudinal flanges of said legs, so as to serve as a guide within which said legs move, a leg member hinged to each end of said guide member, said additional leg members being also formed of angle irons so as to snugly overlie the first mentioned leg when in folded position and means for holding said additional legs in diverging relation relative to each other and to said first mentioned leg.

6. A structure of the character described comprising a longitudinally extendible top including a pair of like end sections composed of a series of spaced bars and an intermediate section composed of a series of spaced bars, the bars of the intermediate section lying between the adjacent bars of the end sections, spacing blocks between said bars, bolts passing through the outer end of the bars of the end sections, on each side of the end sections, the said bolts passing through one end of these strips, a cross bar secured to the other end of the bars of the end sections and turned down over the edges thereof, being positioned within the strips, studs secured to said ends of said cross bars and passing through said strips, leg members pivotally mounted on said bolts and brace members pivotally mounted on said studs and connected to said leg members.

In testimony whereof I hereunto set my hand in the presence of two subscribing witnesses.

MAER HERMAN.
